CLOSURE MECHANISM

Jacques Muller, La Garenne-Colombes, France

Application October 18, 1937, Serial No. 169,750
In France October 22, 1936

5 Claims. (Cl. 137—68)

This invention relates to improvements in the method and in the apparatus for the closing of tanks and comprises closure mechanism for valves of reservoirs or tanks adapted to contain a liquid. Mechanism is provided for opening and setting the closure valve in open position in conjunction with mechanism adapted to indicate the level of liquid in the tank and tripping or release mechanism responsive to the level of liquid in the tank for tripping the closure mechanism and permitting closure of the valve when the desired liquid level is attained. The invention further comprises a safety device by which the closure valve is closed after a certain level of liquid in the tank is reached, in the event that the tripping mechanism should fail to operate for any reason. There is further provided mechanism which opens the closure valve when the tank becomes empty or nearly so. Mechanism is further provided to permit opening of the closure valve at any time regardless of the level of the liquid in the tank.

One object of the invention is to provide a closure for tanks or reservoirs adapted to contain a liquid which is automatic in operation and which may be set to close at any desired predetermined level of liquid.

A further object of the invention is to provide a remote reading indicating means capable of showing at all times the liquid level in the tank.

A further object of the invention is to provide a closure valve mechanism wherein the force necessary to effect the closure of the valve is derived from the pressure of the liquid within the tank and not from the release mechanism which has merely the function of liberating the valve to permit it to close.

A further object of the invention is to provide in conjunction with a closure valve means to open the valve when the tank is substantially empty and further means to permit opening of the valve at any moment irrespective of the level of liquid in the reservoir or tank closed by the valve.

A further object of the invention is to provide in a device of the class described safety mechanism whereby in the event that the tripping mechanism should fail to function, the valve will be closed after a certain predetermined level of liquid has been attained.

Whilst several objects of the invention have been specifically set forth, reference should be had to the accompanying text and drawings from

which other objects and advantages of the invention will become apparent.

For a clearer understanding of the invention reference should be had to the accompanying drawings in which, as much as possible, like elements have been designated by like reference numerals in the various figures and embodiments of the invention, in which:

Figure 1 is an embodiment of the invention designed to be electrically controlled, 10

Figure 2 is a further embodiment of the invention designed to be hydraulically controlled, and

Figure 3 is another embodiment of the invention designed to be mechanically controlled.

Referring to Figure 1, 1 designates a tank or reservoir provided with a body 2 immersed or dipping therein, so disposed as to be acted on by the pressure of the liquid that the tank or reservoir is adapted to contain. The body 2 is capable of limited vertical movement and is guided by 20 any means appropriate in a housing 3 more or less inclosing the body, but arranged to permit access of the liquid therethrough. The body 2, which may be of hollow cylindrical form or hollow rectangular form or of any desired configuration, 25 is provided with a bridge 4, designed to be moved upwardly and downwardly with the body in response to the changes of liquid level. Externally of the reservoir is provided a U bracket 5 having a set screw 6 provided therein between which set 30 screw and the bridge 4 are disposed a series of carbon or graphite sheets or blocks forming a variable resistance or carbon rheostat.

It is obvious that on movement of the body 2 in response to changes of liquid level in the 35 reservoir the carbon or graphite sheets or blocks will be pressed against each other with varying degrees of force depending on the position of the body 2. For the purpose of precluding access of the liquid to the rheostat 7, the same is enclosed within a bellows 8, 9, of any suitable material. The upper edge of the bellows 8 is affixed to the edges of the opening in the reservoir through which the rheostat depends whilst the lower edge of the bellows 8 and the upper edge 45 of the bellows 9 are sealed to the upper and lower faces of the bridge 4, thus providing a liquid tight closure for the rheostat.

The rheostat or resistance 7 is disposed in an electrical circuit 10 which may be provided if 50 desired with a closure switch 11. Arranged to be actuated by the circuit 10 is provided a pointer 12 adapted to move over a dial 13 in response to the variations in current resulting from the change in resistance of the rheostat 7. Pivoted 55

at the same point 14 as the pointer 12 is a second pointer 15 likewise arranged to move over a dial 13 and adapted to be adjusted and fixed in position corresponding to the level of liquid desired to be had in the tank. The pointer 15 carries a contact 16 in an electrical circuit 17 comprising a winding 18 and core 19 constituting a solenoid or electro-magnet. The pointer 12 likewise carries a contact 20 which, when brought into engagement with the contact 16, when coincidence of the two pointers 12 and 15 results, is adapted to close the circuit 17.

The reservoir 1 is provided with a hose connection 21 within which is disposed a closure valve 22 intended to be opened to permit the introduction of liquid to the tank or reservoir and closed automatically when a predetermined level of liquid is attained. The valve 22 is provided with a stem 23 operatively connected by rod 24 to an arm 25 pivoted at 26 and carrying a float 27 adapted to be submerged in the liquid. Preferably the hose connection comprises a cylinder 28 fixedly mounted in the reservoir 1 so as to depend therein, the cylinder being provided with clamping jaws 29 at its upper end to facilitate the connection of the filling hose thereto and projecting downwardly into proximity to the bottom of the tank and surrounding the rod 24.

Pivoted to the valve stem 23 at 30 is a latch 31 urged by any known means (not shown) into position such that when the valve 22 is open the latch engages a pin 32 and thus holds the valve in open position. The float 17, as the liquid level rises and operates thereupon tends to draw the rod 24 downwardly to close the valve 22 but is precluded from so doing as long as the latch 31 engages the pin 32.

An armature 33 disposed on an arm 34 pivoted at 35 is adapted to be drawn upwardly by the solenoid or electro-magnet 10-11 when the circuit 17 is closed through the engagement of the contacts 20-16 carried by the pointers 12 and 15 respectively. The arm 34 carries a trip finger 36 so disposed with respect to the latch 31 that on upward movement of the armature 33 the finger 36 will trip the latch and release the valve 14 for closing.

An arm 37 provided with a float 38 is pivoted at 39 and provided with a trip finger 40 which finger is so positioned that when the float 38 moves upwardly due to the action of the liquid in the reservoir thereon, the finger will be moved to trip the latch 31 and consequently release the valve 22. It is also to be noted that the float 38 is disposed in proximity to the top of the reservoir and is designed to operate the latch only in the event that the automatic setting mechanism hereinbefore described fails to trip the latch 31 to permit closure of the valve at the liquid level for which the pointer 15 has been set.

It can be seen that the float 27 disposed in proximity to the bottom of the reservoir will, when the liquid level drops low enough, pivot in a counterclockwise direction about the pivot 26 to urge the rod 24 upwardly to effect opening of the valve 22. In order however to permit the valve to be opened irrespective of the liquid level existing in the tank, further mechanism is provided consisting of an arm 41 pivoted at 42 and operatively connected as at 43 to the latch 31. A setting pin 44 urged upwardly by a spring 45 disposed between the reservoir 1 and a setting knob 46, is disposed adjacent the arm 41 so that when the knob 46 is forced downwardly against the pressure of the spring 45, the rod 44 will en-

gage the arm 41 and swing it counter-clockwise about the pivot 42, thus lifting the latch 31 and permitting it to engage the pin 32 resulting in opening and latching open of the valve 22.

The operation of the embodiment of Figure 1 is as follows:

The pointer 15 is set with respect to the dial 13 for a predetermined liquid level to which it is desired to fill the reservoir. Connection is made through the hose connection 21 to a source of liquid from which the reservoir is to be filled. The valve 22 is opened and latched in position and the filling operation commences. The rise of liquid level in the reservoir operates on the body 2 to displace it and thus modify the resistance 7 of the circuit 10 causing the pointer 12 to move over the dial 13. When the pointer 12 reaches coincidence with the pointer 15, the contacts 20 and 16 engage closing the circuit 17 and thus energizing the solenoid or electro-magnet 10-11. The energization of the latter results in drawing the armature 33 upwardly and tripping of the latch 31 through the finger 36. The pressure of the in-coming liquid acting on the valve 22 or the force of the float 17 acting through the rod 24 on the valve 22 or both brings about a closure of the valve and thus a discontinuance of the filling operation at a point corresponding to the liquid level desired in the reservoir and for which the pointer 15 has been previously set.

Figure 2 shows a device similar to that of Figure 1 wherein the actuation of the closure valve in response to the level of the liquid in the reservoir 1 is brought about through hydraulic mechanism.

Referring to Figure 2, it will be noted that the majority of the elements within the reservoir are provided with reference numerals corresponding to those given to similar elements in the embodiment of Figure 1. In connection with Figure 2, it is to be noted that the filling of the reservoir is intended to take place from underneath and consequently the valve 22 opens downwardly and closes upwardly in contradistinction to the operation of the valve 22 of Figure 1.

In Figure 2, the immersed body 2, when acted upon by the variations of the liquid level in the reservoir 1, operates the pointer 12 through an hydraulic remote control mechanism. This control consists of a deformable element or bellows or cylinder or any other motor means 101, connected through a conduit 102 to a similar deformable organ or bellows 103. The pointer 12 designed to move over a dial 13 may be actuated by the organ 103 in any desired manner so as to move over the dial 13 corresponding to the changes in the liquid level in the reservoir. The pointer 15 which is adapted to be set corresponding to the predetermined desired liquid level to which the reservoir is to be filled, carries a cam 104 pivoted eccentrically at 14 and designed to co-operate with and displace a member 105.

The member 105 is guided for more or less vertical movement and provided with a slot 106 in which engages a fixed pin 107 and a second pin 108 carried by a bar or similar member 109 connected to the deformable organ 103 and adapted to be displaced thereby in response to changes in the liquid level in the reservoir. A hydraulic compensating mechanism is provided for the purpose of compensating the operation of the mechanism heretofore described for variations in the surrounding atmosphere. The compensating mechanism comprises a deformable organ or bellows 110 connected by means of a conduit 111 to 78

a deformable organ or bellows 112 disposed within the reservoir and supported if desired by connection to the lower surface of the top thereof. The bellows 110 of the compensating system is connected to the bar 109 operated by the deformable organ or bellows 103.

The lower portion of the member 105 is cut on a bias as at 113 and depends into proximity to a pin 114 carried by a bar 115 which bar is connected to a hydraulic system comprising a first bellows 116 connected by a conduit 117 to the second bellows 118. The cam 104 is so formed that the member 105 is moved upwardly and thus the biased face 113 moved further away from the pin 114 according as the pointer 15 is set for greater liquid levels. The member may be urged into constant contact with the cam through any suitable means as by a spring (not shown). To the second bellows 118 is pivoted as at 119 one end of the arm 34 pivoted at 35 carrying a trip finger 36, adapted to trip the latch 31, as described with reference to Figure 1. A hydraulic compensating system is also associated with the deformable organ or bellows 116, comprising a deformable organ or bellows 120 connected to the bar 115 and communicating through conduit 121 with a deformable organ or bellows 122.

The operation of the mechanism of Figure 2 is as follows:

On increase of the liquid level in the reservoir 1, the body 2 moves upwardly exerting a pressure through hydraulic system 101—102—103 and causing the pointer 12 to move over dial 13. When the pointer 15 has been set for that liquid level at which closure of the valve 22 is desired, it positions the member 105 with respect to the pin 114 such that when the pointer 12 coincides with the pointer 15, the biased lower portion of the member 105 will have been moved by the deformable organ 103 into contact with the pin 114, thus urging the pin 114 to the right in Figure 2 and exerting through the hydraulic system 116—117—118 a downward pressure on the pivot 19. The pressure causes the arm 34 to swing in a counterclockwise direction and trip the latch 31. The valve 22 is now released for closing and as in Figure 1 the float 27 through the intermediary of the arm 25 moves the rod 24 upwardly to close the valve. As described with respect to Figure 1, there is also provided a safety trip 37—38—39—40, by which, in the event that the automatic trip mechanism fails to operate, the latch 31 will be tripped to permit the valve 22 to be closed. Furthermore as in the device of Figure 1, setting mechanism operated by the button 46 is provided for setting the latch 31 in position to hold the valve 22 open.

Referring to Figure 3, there is shown an embodiment of the invention wherein the tripping mechanism is actuated through the intermediary of a Bowden cable. The body 2 dipping into the liquid in the tank 1 is connected to a rod 201 guided for substantially vertical movement at 202 in the reservoir upper wall. Pivoted to one end of the rod 201, are bell crank levers 203—204 each provided with weights 205—206 and pivoted respectively to links 207—208, the upper ends of which links are pivoted at 209—210 respectively to a fixed pivot. The rod 201 is connected through the intermediary of the core 211 of a Bowden cable, the sheath of which is designated 212, to two pivoted arms 214—215 carrying respectively weights 216—217 and in turn pivoted at 218—219 to links 220—221 pivoted at their lower ends to fixed pivots 222—223. Beyond the

pivot 213, the core 211 of the Bowden cable extends upwardly through a guide 224 and carries an abutment 225.

As in Figures 1 and 2 there is provided a pointer 15 associated with a dial 13, which pointer is adapted to be set to the position corresponding to the desired level to which the tank or reservoir is to be filled. Furthermore as in Figures 1 and 2, there is provided a pointer 12 which pointer, in Figure 3, is actuated from either of the arms 214—215 through any desirable manner as, for instance, by a link 226, so as to pass over the dial 13 and indicate at all times the liquid level in the reservoir. The pointer 15 is provided with a cam 104 disposed in an operative arrangement with respect to an organ 105 which is urged into contact with the cam by spring 112. The organ 105 is provided with a slot 106 and a pivot 227 engages in a slot. The organ 105 carries a finger 228, projecting to the right in Figure 3 into proximity to the abutment 225 and between said abutment 225 and an abutment 229 connected to the core 230 of a Bowden cable which core is likewise connected to the trip arm 34.

The cam 104 is so formed that the wedge shaped finger projects progressively less and less to the right between abutments 225 and 229 according as the pointer 15 is set for greater liquid levels.

The operation of the device of Figure 3 is as follows:

In the setting of the pointer 15 with respect to the dial 13, corresponding to the liquid level at which closure of the valve 22 is desired, displacement of the pointer effects through the cam 104 setting of the organ 105 with respect to abutment 225—229. Weights 205—206 urge the core 211 of the cable downwardly in opposition to the effect of the body 2 which tends to rise as the liquid level in the reservoir or tank rises. As the body 2 rises through the intermediary of the core 211, arm 215 and link 226, it transmits motion to the pointer 12 causing the pointer to move over the dial 13. The arrangement is such that when the pointer 12 coincides with the pointer 15, the abutment 225 has moved upwardly sufficiently to abut the finger 228 of the organ 105 and force it against 229. The result is that the abutment 229 is moved upwardly and by virtue of its connection to arm 34 causes the trip finger 36 to trip the latch 31 and release the rod 24 so as to permit closure of the valve 22.

Whilst three embodiments of the invention have been illustrated and described, it is particularly to be borne in mind that these embodiments are merely illustrative of the nature of the invention and are not to be taken as limitative of the scope thereof which is defined in the appended following claims.

What is claimed is:

1. In a reservoir having a closure valve, means for opening and holding the valve in open position, means responsive to the level of liquid in the reservoir for releasing the holding means and further means responsive to the liquid level in the reservoir for releasing the holding means if the last named means fails to function.

2. In combination with a reservoir having a closure valve therefor, a latch adapted to hold the valve in open position, float means tending to close the valve, float means distinct from said first named float means adapted to release the latch after a predetermined level of liquid is reached and further means responsive to the

liquid level in the tank adapted to be preset to release the latch at a predetermined liquid level.

3. In combination with a tank having a closure valve therefor, a latch adapted to be set to hold the valve in open position, means responsive to the liquid level in the reservoir for setting the latch and manual means for setting the latch, means responsive to the level of liquid in the reservoir for releasing the latch and means adapted to be preset to release the latch at any desired liquid level in the reservoir.

4. In combination with a liquid reservoir and a closure valve therefor, a latch adapted to be set to hold the valve in open position, float means responsive to the level of the liquid tending to closure the valve, means responsive to the level of liquid in the reservoir adapted to release energy to trip the latch, means for setting the liquid

level at which the release means comes into operation and float means adapted to trip the latch in the event that the release means fails to operate.

5. In combination with a reservoir having a closure valve therefor, a latch adapted to be set to hold the valve in open position, float means responsive to the liquid level in the reservoir for setting the latch, pressure responsive means independent of said float means for releasing energy to trip the latch, and additional pressure responsive means acting upon said first-named pressure responsive means to offset the effect which variations in the surrounding atmosphere would otherwise have upon operation of said first named pressure responsive means.

JACQUES MULLER.
